UNITED STATES PATENT OFFICE.

CHARLES D. GALLOWAY, OF PHILADELPHIA, PENNSYLVANIA.

HANDLE FOR STORAGE BATTERIES.

Application filed June 14, 1923, Serial No. 645,254. Renewed October 22, 1925.

To all whom it may concern:

Be it known that I, CHARLES D. GALLOWAY, a citizen of the United States, residing at Philadelphia, in the county of Philadelphia and State of Pennsylvania, have invented a new and useful Improvement in Handles for Storage Batteries, of which the following is a specification.

The invention is particularly applicable to storage battery containers which are made of rubber or rubber composition or like material and which are intended for use without wooden cases or boxes and which are frequently employed on automobiles.

The principal object of the present invention is to provide attachments for such composition jars or containers which will serve either as handles or hold-downs or both. Another object of the present invention is not only to provide for convenient application and removal of the handle or hold-down attachments but also to provide for a simple, comparatively inexpensive, strong and durable construction and arrangement thereof. Other objects of the invention will appear from the following description.

Generally stated, the invention comprises the combination with a recess and cleat provided at the end wall of the composition container of a metallic fitting consisting of a knee of which one part is provided with feet engaging the recess and of which the other part is provided with a clip co-operating with the cleat, the fitting being adapted for snapping into and out of attachment with respect to the container and wall. The invention also comprises the improvements to be presently described and finally claimed.

In the following description reference will be made to the accompanying drawings forming part hereof and in which—

Figure 1 is an end view of a storage battery jar or container embodying features of the invention.

Fig. 2 is a sectional view taken on the line 2—2 of Fig. 1, and

Fig. 3 is a sectional view taken on the line 3—3 of Fig. 1.

In the drawings 1 is a recess or undercut, and 2 is a cleat provided in the end wall 3 of a storage battery jar or container of the kind, for example, that is made of composition, used without a wooden case, and contains integral partitions. The wall of such

a jar is usually reinforced by making it thicker around the top as indicated at 4, and this reinforcement may be continued at each side of the recess 1 as at 5 and may be made of reduced thickness opposite the recess 1, as at 6. The cleat 2 is shown as terminating in abutments 7 and as provided with a vertical wall as at 8. The metallic fitting consists of a knee or angularly bent portion 9 of which one part 10 is provided with a foot or claw engaging the recess 1. The foot or claw is shown as forked which is a matter of convenience for the accommodation of the hold-down 11. The foot or claw is also shown as provided with a straight shank 12 adapted to bear upon the face of the end wall of the jar or container. The other part of the knee is provided with a clip 13 having at its end a lip 14. 15 is a handle shown as struck up from the fitting, and 16 is an opening provided in the fitting for the hold-down 11. 17 is a slot provided in the clip for the insertion of a tool.

The fitting is snapped, for example, by 80 springing it into place on the jar wall, as shown in the drawing, the claw 10 being hooked in the recess 1, the lip 14 riding on the curved surface of the cleat until it runs off that surface permitting the clip, or more accurately, the straight shank portion 18 of the clip to contact with the straight portion 8 of the cleat, thus the clip and cleat constitute a firm and strong coupling which along with the claw 10 and recess 1 connects the 85 fitting and jar not only when lifted by the handle but also when held by the hold-down. The abutments 7 oppose any lateral relative motion of the parts. When it becomes necessary to detach the fitting, for example, 90 when the fitting is worn out and should be replaced by another, a screw driver or other appropriate tool may be inserted in the slot 17, and with the knee 9 as a fulcrum, the fitting can be snapped off. In general it 95 may be said that the fitting and the jar wall are connected together by two opposed hook elements provided on the fitting and adapted to engage the cleat elements on the jar, the engagement and disengagement being provided for by the angular form of the fitting 100 which can be made in one piece and which can be sprung sufficiently for the purpose. The element 2 at the top of the jar and the wall 19 of the recess constitute spaced cleat 105 elements on the jar which co-operate with the opposed hook elements on the fitting.

It will be obvious to those skilled in the art to which the invention relates that modifications may be made in details of construction, arrangement and mere matters of form without departing from the spirit of the invention which is not limited as to those matters or otherwise than as the prior art and the appended claims may require.

I claim:

- 10 1. In a storage battery container the combination of oppositely disposed spaced cleats provided on the container wall, and a metallic spring fitting provided with confronting hook elements and adapted for snapping said hook elements into and out of attachment with respect to the wall.
- 15 2. In a storage battery container the combination of a cleat having a curved surface and a flat surface and provided on the top 20 of a wall of the container, a recess provided in the face of the wall of the container and which constitutes an undercut portion, and a metallic spring fitting in the form of a knee and one part of which is provided with a 25 claw adapted for engagement with the undercut portion and the other part of which is provided with a curved clip having a lip, and said fitting having a straight shank, substantially as described.
- 30 3. In a storage battery container the combination of a curved cleat provided on the top of a wall of the container, a recess pro-

vided in the face of the wall of the container, and a metallic spring fitting having a claw which is adapted to engage in the recess and which is provided with a straight shank for contact with the surface of the wall and having a clip adapted to engage with the cleat.

4. In a storage battery container the combination of two cleats whereof one is provided at the top of a container wall and whereof the other is formed by a recess provided in the face of the container wall, and a metallic spring knee having a clip for engagement with one of said cleats, and a claw adapted to engage the other of said cleats and forked to provide a recess for a hold-down clamp, substantially as described.

5. In a storage battery container the combination of spaced cleats provided respectively at the top and face of a container wall, and a metallic spring knee having a claw and a clip for co-operation with said cleats and provided with a handle and with a recess for a hold-down clamp.

6. In a storage battery container the combination of cleats on the container end wall, and a metallic spring knee structure having hook elements for co-operation with the cleats and provided with a tool receiving slot arrangement to co-operate with the knee as a fulcrum, substantially as described.

CHARLES D. GALLOWAY.
